DESIGN FOR CHENILLE SLACKS

Melvin D. Brod, New York, N. Y.

Application March 19, 1940, Serial No. 91,066

Term of patent 3½ years

To all whom it may concern:

Be it known that I, Melvin D. Brod, a citizen of the United States and resident of New York city, in the county of New York and State of New York, have invented a new, original, and ornamental Design for Chenille Slacks, of which the following is a specification, reference being had to the accompanying drawing, forming a part thereof.

Fig. 1 is a front elevational view of chenille slacks, showing my new design.

Fig. 2 is a side elevational view of the same. Fig. 3 is another side elevational view of the same. The back of the garment is conventionally plain.

I claim:
The ornamental design for chenille slacks, as shown and described.

MELVIN D. BROD.
